UNITED STATES PATENT OFFICE.

JOHN TARANTO, OF WALTHAM, MASSACHUSETTS, ASSIGNOR TO DRAPER CORPORATION,
OF HOPEDALE, MASSACHUSETTS, A CORPORATION OF MAINE.

SHUTTLE-FEELER FOR LOOMS.

1,341,026.

Specification of Letters Patent. Patented May 25, 1920.

Application filed November 15, 1919. Serial No. 338,191.

To all whom it may concern:

Be it known that I, JOHN TARANTO, a citizen of the United States, and resident of Waltham, county of Middlesex, State of Massachusetts, have invented an Improvement 5 in Shuttle-Feelers for Looms, of which the following description, in connection with the accompanying drawing, is a specification, like characters on the drawing representation, like characters on the drawing representation,

10 senting like parts.

This invention relates to improvements in shuttle feelers for looms and the object thereof is to provide a novel shuttle feeler which will act on detection upon an improperly boxed shuttle, through the warp stop mechanism to effect a stoppage of the loom. A further object of the invention is to provide a shuttle feeler of the character above described which can be readily applied 15 to a usual commercial type of loom without modification of the usual mechanisms of the loom.

The present invention is disclosed herein as embodying the well known Crompton and 20 Knowles type of loom, but is applicable to other commercial types of looms.

The object of the invention is to provide a supplemental or additional stop mechanism, to the usual protector mechanism for looms, 25 which will insure the stoppage of the loom when the shuttle is improperly boxed. The usual protector mechanism comprises an arm which rests against the binder of the shuttle box and when the shuttle is properly positioned 30 in the box the arm is actuated in such a manner as to remove the dagger from the path of a bunter which actuates the knock-off mechanism. It is possible that the shuttle may enter the box sufficiently to 35 operate the protector mechanism, but still not far enough to inclose the shuttle wholly within the box. In such case it is not properly positioned to be engaged by the picker stick and receives the action of the picker 40 stick only during the latter portion of the movement of said picker stick so that the shuttle may be forced only part-way across the loom, thus causing a smash when the lay beats up.

45 In looms of the Crompton and Knowles type, and in other looms, which are provided with transferring mechanism, the shuttle may enter the box sufficiently to actuate the protector mechanism so as to prevent knock-off, but still not far enough to be properly 50

positioned in relation to the transfer mechanism. The present invention contemplates the provision of an additional stop mechanism which will be operated by engagement with the end of the properly positioned 60 shuttle and insure knock-off. The present invention may also be employed in automatic filling replenishing looms which embody a shuttle feeler since the shuttle feeler mechanism merely acts to prevent transfer 65 and not to effect the stoppage of the loom.

It will thus be seen that the present stop mechanism constitutes an additional safeguard which will insure the proper operation of the loom and more certainly prevent 70 the possibility of smashes. Furthermore, by causing the stoppage of the loom if the shuttle is improperly boxed, either by insufficient picker action or rebound, if the proper operation of the transferring mechanism in 75 automatic filling replenishing looms, is insured, and the proper picking of the shuttle in looms, whether of the automatic filling replenishing type or the ordinary or box type of looms, is safeguarded. 80

In automatic filling replenishing looms the present invention may be employed as a substitute for the usual shuttle feeler mechanisms as will be obvious and when so used will effect the stoppage of the loom upon 85 detection of an improperly boxed shuttle, instead of merely preventing transfer.

Other objects and features of the invention will more fully appear from the following description and the accompanying drawings and will be pointed out in the annexed 90 claims.

A preferred embodiment of the invention is disclosed herein as applied to the well known Crompton and Knowles type of loom 95 embodying a warp stop mechanism, certain portions of which are disclosed in the patent to Wyman, No. 665,713, granted January 8th, 1901.

In the drawings:

Figure 1 is a side elevation of a portion of a loom having a preferred embodiment of my invention applied thereto, the mechanisms not directly involved in the operation of the invention being omitted for the purpose of clearness. 100

Fig. 2 is a detail plan view of the connection between sections of the extensible feeler.

The invention as illustrated in the accompanying drawings as applied to the well 110

known Crompton and Knowles type of loom, the portions of which illustrated in the drawings comprise the usual side frame 1, breast beam 2 and arch bar 3 connecting the sides 5 of the frame, the lay 4 which is carried by the swords 5 and oscillated by the pitman 6 in the ordinary manner. A shuttle box 7 is carried upon the lay 4 and receives the usual shuttle 8 which is reciprocated across 10 the race upon the lay by the usual picker sticks, not shown.

The loom illustrated is provided with a shipper lever 9 which is retained in a notch in a shipper plate 10 secured to the end of the breast beam and desirably is formed 15 with a resilient lower portion 11 normally tending to actuate the shipper to stop the loom when disengaged from the notch.

Suitable knock off mechanism is provided 20 which as illustrated comprises a hook shaped member 12 having a plate engaging the shipper 9, the hook 12 being carried at the end of a link 13 which is connected at its opposite end to the upper end of a rocker 14 which is pivotally mounted upon a shaft 15 carried by a suitable boss 16 mounted upon or integral with side frame 1. The rocker 14 normally is held in vertical position so that a lug 17 projecting from it normally engages a flange or ear 18 projecting 25 upwardly from the boss 16. A dagger 19 projecting laterally from a sleeve 20 pivotally mounted upon a stud 21 upon the upper end of the rocker 14 is adapted to cooperate 30 with a bunter 22 carried by a bracket 23 secured to the lay and depending therefrom. The dagger 19 normally is held out of the path of the bunter 22, preferably being held above said path by supporting arm 24 35 underlying a shoulder 25 on said collar, the supporting arm 24 being carried by a shaft 26 journaled in the rocker 14 and having at its opposite end an actuating arm 27 which is connected by a link 28 to the warp stop 40 mechanism, the construction being such that upon endwise movement of the link 28 in either direction the supporting arm 24 will be rocked from beneath the supporting shoulder 25 of the collar 20 and will permit 45 the dagger 19 to drop into the path of the bunter upon the rearward movement of the lay. When therefore the bunter 22 engages the dagger 19 it will oscillate the rocker 14 about its pivot 15 thereby drawing upon the 50 link 13 and causing the latter to release the shipper from the notch in which it is normally held during the operation of the loom. The resilient portion 11 of the shipper thereupon moves the shipper away from 55 the side of the loom. The shipper by such movement is arranged to actuate the usual member 29 which controls a clutch, or belt shifter and brake for stopping the loom.

In order that subsequent oscillations of 60 the lay may not repeatedly actuate the

knock-off mechanism automatic means are provided for restoring the dagger to its inoperative position. The means illustrated for effecting this purpose comprises an arm 30 having a head 31 which is clamped upon the member 29, the arm 30 being positioned to engage a downwardly extending arm or tail 32 connected with or formed integral with the collar 20, these parts being so constructed that upon lateral movement of the 75 member 29 the arm 30 will actuate the tail 32 to rock the sleeve 20 sufficiently to raise the dagger above the path of the bunter whereupon the supporting arm 24 will again engage the shoulder 25 on said sleeve and 80 retain the dagger in inoperative position.

The warp stop mechanism as illustrated is substantially identically disclosed in the Wyman Patent No. 665,713 aforesaid and comprises a casing 33 which contains the 85 usual drop wires and supports at its top the lease-rods 34, 35 over which the warps are carried, the drop wires being supported by the warps in the usual manner and adapted upon breakage of a warp or to great slackness therein to drop into the path of a vibrator which is secured to a shaft 36 journaled in a bracket 37 pending from the casing 33, the shaft 36 being oscillated through an arm 38 secured thereto.

Movement is imparted to the arm 38 of the vibrator through a transmitter consisting of a lever 39 having at its lower end a slot 40 which receives a stud 41 upon the end of arm 38. The transmitter lever is pivoted upon a stud 42 extending outwardly from the elbow of an actuator in the form of a bell crank lever 43 which is pivotally mounted upon a stud 44 projecting from the main frame of the machine. The other 100 arm 45 of the bell crank lever is connected to a link 46 which is reciprocated from a cam upon a cam shaft of the loom. The transmitter 39 has an upwardly projecting arm 47 provided with a stud 48 which normally is positioned in axial alinement with the axis of the pivot 44 of the bell crank actuator and the link 28 is connected to the stud 48. A spring actuated plunger 49 or positioning device having a flat face engaging the side of the transmitter normally tends to hold said transmitter in such position that the stud 48 to which the link 28 is connected is in axial alinement with the pivot upon which the actuator is mounted. 110 In the operation of the warp stop mechanism the reciprocation of the link 46 causes an oscillation of the actuator 43 about its pivot 44 thereby imparting through the transmitter 39 a vibratory motion to the 115 arm 38 of the vibrator, and causing the vibrator to move beneath the drop wires which are supported upon the warps. When, however, a drop wire falls or is let down by reason of the slackness of the 120

warp into the path of the vibrator, the vibrator will be arrested and the movement of the actuator thereupon will rock the transmitter about its pivotal stud 42, thereby 5 moving the stud 48 at its end in an arc about the pivot 42 so that the link 28 will be thrust endwise in one direction or the other sufficiently to release the supporting arm 24 from its engagement with the 10 shoulder upon the dagger supporting sleeve 20 thereby permitting the dagger 19 to drop into the path of the bunter so that the latter will rock the arm 14 to knock off the shipper as above described. The mechanism 15 thus described may be and is a usual form employed in the commercial looms of the Crompton and Knowles type.

The present invention consists in applying to the warp stop mechanism a shuttle feeler 20 which is adapted to initiate the action of the knock-off mechanism through the warp stop mechanism when said shuttle feeler engages an improperly boxed shuttle. The shuttle feeler mechanism which is illustrated 25 as applied to the loom having the warp stop mechanism above described is of a very simple character and comprises an arm or a rod preferably made in extensible sections 50, 51, one section being connected to the stud 48 upon the end of the transmitter and the other section provided with the hook-like extension 52 positioned adjacent the mouth of the shuttle box 7. If, therefore, the shuttle 30 does not sufficiently enter the box, or if it re- 35 bounds after entering the box so as to project beyond the end of the box it will engage the portion 52 of the shuttle feeler as the lay moves forward in its beat up and will pull the shuttle feeler lengthwise thereby rock- 40 ing the transmitter 39 forward, acting through the link 28 to rock the supporting arm 24 from beneath the shoulder on the dagger supporting collar 20 so that the dagger 45 will drop into the path of the bunter 22, which upon the rearward movement of the lay will operate the knock-off mechanism. Any suitable means may be provided for supporting the shuttle feeler. As illustrated herein the section 50 of the shuttle feeler is 50 slidably mounted in a suitable guide 53 in a bracket 54 secured to the arch bar 3.

Any effective means may be employed for extensibly adjusting the shuttle feeler. In a preferred embodiment of the invention ill- 55 lustrated in the drawings the sections 50, 51 of the shuttle feeler extend through sleeves 55, 56 which are provided with suitable clamping screws 57, 58 which, when set up,

will clamp the sections 50, 51 firmly against each other and to the collars. 60

It will be understood that the embodiment of the invention disclosed herein is illustrative and not restrictive and that the invention may be applied to different forms of warp stop mechanism and that other feeler constructions may be employed within the meaning and scope of the following claims. 65

Having thus described my invention what I claim as new and desire to secure by Letters Patent is: 70

1. In a loom comprising a lay and warp stop mechanism, a shuttle feeler connected to said warp stop mechanism and operable upon detection of an improperly boxed shuttle to actuate said warp stop mechanism 75 to effect a stoppage of the loom.

2. In a loom comprising a lay and warp stop mechanism including a vibrator, an actuator, and a transmitter, and means operable by the movement of said transmitter for effecting a stoppage of the loom; a shuttle feeler connected to said transmitter operating upon detection of an improperly boxed shuttle to actuate said transmitter to cause a stoppage of the loom. 85

3. In a loom comprising a lay and warp stop mechanism including a vibrator, an actuator, and a transmitter, and means operable by the movement of said transmitter for effecting a stoppage of the loom; a shuttle feeler comprising a rod having a shuttle engaging member positioned adjacent the mouth of the shuttle box, said rod being connected at its opposite end to said transmitter whereby upon engagement 95 of said shuttle feeler with an improperly boxed shuttle during the forward movement of the lay said transmitter will be actuated to effect the stoppage of the loom. 90

4. In a loom comprising a lay and warp stop mechanism including a vibrator, an actuator, and a transmitter, and means operable by the movement of said transmitter for effecting a stoppage of the loom; a shuttle feeler comprising a shuttle engaging 100 member and an extensible member connected to said transmitter whereby said shuttle engaging member may be properly positioned in relation to the path of the shuttle and said transmitter operated upon detection of an 105 improperly boxed shuttle to cause a stoppage of the loom. 110

In testimony whereof I have signed my name to this specification.

JOHN TARANTO.
